Attorney

UNITED STATES PATENT OFFICE

ALFRED G. F. KUROWSKI, OF BROOKLYN, NEW YORK, ASSIGNOR TO UNDERWOOD ELLIOTT FISHER COMPANY, OF NEW YORK, N. Y., A CORPORATION OF DELAWARE

TYPEWRITING MACHINE

Application filed June 28, 1926. Serial No. 118,996.

This invention relates to typewriting machines and is an improvement on the construction shown and described in a Patent No. 1,501,671, issued to me on July 15, 1924, and is especially directed to improvements in platen-control means whereby envelopes or worksheets, when inserted into a machine, may be brought to the printing line at a single sweep of the platen.

10 Sometimes the inserters are given a quick start, thereby causing the driving pawl to miss the first ratchet tooth. Sometimes the sheet is advanced farther than desired, due to the rapid motion of the rotating lever, the 15 inertia of the parts causing the platen to be over-rotated.

A feature of the present invention is to eliminate both of these defects, thereby permitting the inserter to be operated at a maximum speed.

Another feature of the invention is the provision of an extremely efficient inserter of greatly simplified construction, which may be readily attached to a standard Underwood 25 typewriter.

Another feature of this invention relates to the self-contained and enclosed features of the mechanism forming a complete attachment which may be made and sold separately 30 from the typewriting machines, but which may be quickly applied thereto when platen-sweeping operations are to be performed.

Important features of the invention are found in simpler and more positive ratchet-pawl pickup and locking means, more substantial and effective means for controlling the return of the operating handle, and simplified scale or gage markings to which the parts are set for a predetermined line-space 40 sweep or throw of the platen. A bracket having means whereby the device may be adjusted to fit different machines is also a feature.

In carrying out my invention the structure 45 may include a bracket adjustably secured to the platen-frame, said bracket having a depending outside flange to which a supporting plate for the operative mechanism is bolted, and to which an arcuate indicator or scale plate is welded or otherwise fastened.

A segmental gear rack or plate is spaced in parallel relation with the above mentioned supporting plate and is secured thereto by cross screws passing through the plates and through spacing sleeves and constitute fixed 55 posts.

A centrally arranged shaft or pin is fixedly supported at its ends by the plates and carries an oscillatory operating handle with which is formed a sleeve or hub projecting 60 inwardly on said shaft, and to the rear end of this sleeve is keyed a grooved guide wheel on which a spiral spring is supported, having one of its end fast with the wheel and the other end secured to a fixed point on the supporting plate.

Free to rotate on the said sleeve, between the operating handle and the spring guide wheel, are ratchet and gear wheels connected to rotate together. The ratchet wheel is 70 driven by a spring-pulled pawl carried on the operating handle while the gear wheel is meshed with a pinion mounted on the platen axle to drive the same.

A freely mounted rock-plate is also supported on the cross shaft or pin between the segmental gear plate and the operating handle and carries a pivoted toothed dog, spring-pulled to normally hold its teeth in locking engagement with the gear rack to 80 hold the parts at a predetermined position by which a desired sweep or throw of the platen is achieved. The rock plate may also carry a pin against which the operating handle is normally held by the spiral spring above 85 referred to. This pin has an enlarged head which is positioned to normally engage a tail extension on the ratchet pawl to hold its nose above and out of engagement with the ratchet teeth. The rock-plate further carries a pointer or finger to permit of the parts being locked accurately at a desired scale line.

Other features and advantages will herein- 95 after appear.

In the accompanying drawings,

Figure 1 is a plan view showing the invention applied to the platen-frame of a standard typewriter, the parts of the device be- 100

ing set for a platen movement of eight line spaces.

Figure 2 is a side elevation of the device and in the position shown in Figure 1, the platen-operating finger-wheel being removed.

Figure 3 is a vertical sectional elevation, the section being taken about on the line 3-3 of Figure 2.

10 Figure 4 is a fragmentary diagram showing the handle at the limit of its forward throw, the ratchet pawl being interlocked with the teeth of its wheel to positively stop the rotation of the parts.

15 Figure 5 is a fragmentary detail showing the normal raised position of the ratchet pawl.

20 Figure 6 is a similar view showing the quick pickup of the pawl at the start of the handle throw.

The usual platen 10 is carried on an axle 11 journaled in the ends of a platen-frame 12, to which is connected a paper table 13 in the usual manner.

25 Coacting with the platen to feed envelopes or work-sheets around the platen are feed-rolls 14. The platen may be rotated by hand-wheels 15 carried on the ends of the platen axle, or the usual line-space mechanism may 30 be employed, which includes a line-space wheel 15^a fixed to the platen axle and rotatable by a feed pawl 16 pivoted on a slide 17 driven by a line-space lever 18.

35 The work-sheet may carry a series of similar forms to be typed successively, the distance from the last typed line on one form to the first line to be typed on the next form being constant or uniform. During the typing operation of a form the platen may be 40 line-spaced by the hand-wheels 15 or by the usual line space mechanism operated by the lever 18.

45 However, when a form has been typed it is necessary to rotate the platen to present the first line of the next succeeding form at the printing line, and it is desirable that the sweep or throw of the platen through this distance shall be quick and accurate, and to accomplish this I provide a bracket 19 supported on the platen-frame 12 and adjustably secured thereto by a screw 20 passing through a slot 21 into said frame, and a screw 22 threaded through the top plate of the bracket 50 and resting on the top face of said frame, so that by manipulating this latter screw the center of the platen may be vertically adjusted so the device can be used in connection with different machines, as will be seen more clearly below.

55 The bracket includes a depending outside flange 23 to which a supporting plate 24, carrying an arcuate scale plate 25, is bolted, said scale plate having simple single line markings 26, easy to read, by which the parts

may be set to effect a predetermined sweep or throw of the platen.

A segmental gear rack or plate 27 is arranged in parallel relation with the supporting plate and is secured thereto by cross screws or bolts 28 passing through spacing sleeves 29.

60 A centrally arranged shaft or pin 30 is fixed in the plates by riveting and carries an oscillatory operating lever or handle 31 with 75 which is integrally formed a sleeve or hub 32 projecting inwardly on the shaft, and keyed to the end thereof is a grooved guide-wheel 33 on which a round spiral spring 34 is supported, having one of its ends fast with 80 the guide-wheel and the other end secured as at 35 to the supporting plate 24.

65 Compactly mounted on the sleeve 32, between the operating handle 31 and guide-wheel 33, are ratchet and gear wheels 36 and 85 37 respectively, which are connected to rotate together.

70 The ratchet wheel is driven by a pawl 38 having a tail extension 39, and is loosely carried on a screw or pin 40, and a spiral pull spring 41 is attached at one end to an ear 42 on the pawl and to a fixed pin 43 on the operating arm.

75 The gear wheel 37 is constantly in mesh with a smaller gear 44 secured as by its hub 44^a in a suitable manner to the platen axle 90 to drive the same.

80 A rock-plate or stop member 45 is loosely mounted on the cross-shaft 30, between the segmental gear plate 27 and the operating handle, and carries a pivoted dog 46 provided with teeth 47 normally held in interlocked relation with teeth of the segmental gear 27 by a spiral pull spring 48. The pivoted dog has a struck-up angular part or finger piece 49 by which it may be swung upwardly to disengage its teeth from the gear rack when the parts are to be set in a new position to change the platen sweep or throw.

85 The rock-plate also may have a struck-up angular part or finger-piece 49^a at the top, so that an operator by pressing the two finger-pieces 49^a and 49 together may easily manipulate and set the stop-member 45.

90 The rock-plate also carries a pin 50, against which the operating handle is normally held by the round spiral spring 34 tensioned around the guide-wheel 33.

95 This pin 50 is formed with an enlarged head 51 which normally engages the tail 39 of the pawl 38 to hold its nose out of engagement with the ratchet wheel 36. Obviously, when the operating handle begins a forward swing away from the pin 50, the nose of the pawl 38 will be quickly drawn into engagement with the teeth of the ratchet wheel by the tensioned pull-spring 41, thus securing accurate sweeps or throws of the platen. Attached to an inwardly directed extension of the rock-plate is a pointer 52 which

ranges forwardly over the arcuate scale plate 25, by which the parts may be accurately set at a desired point to obtain a desired sweep or throw of the platen.

5 A stop screw or pin 53 is passed through the segmental gear plate 27 and projects into the path of the rock plate 45, against which it rests when the parts are in the rearward or inoperative position. When employing this 10 invention on some typewriting machines, this screw may be removed and the range of operation of the parts increased.

Particular features are found in the arrangement and design of the adjustable stop- 15 means for the operating lever. The rock-plate or stop-member 45 has the preferred shape of an inverted L, the vertical shank of which is substantially in line with the lever 31 when the latter is in operative position.

20 The horizontal shank of the L-plate ranges backwardly and has a bent-over angular part at the top which conveniently serves as the finger-piece 49^a and houses the toothed dog 46 with its spring 48. The dog points backwardly and its pivot-point is located rather close to the teeth of the gear-rack 27, but so that the backward throw of the lever 31 will not cause the teeth of the dog 46 to be pushed out of engagement with the gear-rack 27.

25 The horizontal shank of the L-plate ranges backwardly not only to house said pawl 38, as shown, but also to present the stop 50 as an abutment to the rear edge of the lever 31. In this connection it is noted that after removing 30 the stop-screw 53, the lever 31 is held in extreme rearward inoperative position, the L-shaped stop-plate then being allowed to fairly hug around the rear cross-screw 28. Close range between said screw 28 and the 35 lever 31 is obtained and the lever may range all over the gear-rack between the limits of the screws 28.

The horizontal shank of the rock-plate has a lateral extension or tab 54, which carries 40 the pointer 52. The rock-plate 45, the tab 54 and the pointer 52 then form a U-shaped structure (see the top view of Figure 1), within which lever 31 and its driving pawl 38 are conveniently lodged. The pointer 52 may 50 be fastened as by screw 55 and flexed so as to extend forwardly into proper visible relation with the scale-plate 25.

The design of the device includes further features. The attachment includes the plates 55 24 and 27 rigidly spaced from each other to form a framework fit to carry both ends of the shaft or axle 30 of the rotating mechanism. Moreover, the plates are to house the mechanism so as to present a unit which is 60 compact, handy and designed for ready attachment to the platen-carriage. The plate or gear rack 27 forms the smooth outer shield plate of the device. The arcuate scale-plate 25 extends (see Figure 3) from plate 24 to- 65 wards the outer plate 27, and encases opera-

tive parts of the mechanism while providing a clearance for the operation of the lever or handle 31 which is suitably located adjacent the outer plate 27.

Plate 27 when formed as a gear-rack gives 70 opportunity for the provision of the adjustable stop, which itself is extremely simple, compact, and handy, as described above. The hub or sleeve 32 extends from the lever 31 inwardly and under the scale-plate 25 so that 75 the guide-wheel 33 upon said hub is set closely against the plate 24, and the spring 34 may be suitably anchored upon that plate as shown. This spring 34 is accessible, has positive effectiveness, and is easily attached, 80 while extremely compact in arrangement due to its being wound around the guide-wheel 33. The guide-wheel again confines the wheels 36 and 37 to their proper place upon hub 32. It will be noted that the novel provision of the guide-wheel and the associated spring 34 is furthermore useful in that it renders the returning spring more independent from the location of the operating lever, thus 85 affording new possibilities for design. In 90 the present case the spring may be spaced from the lever by said hub 32.

The forward throw of the lever 31 is limited when the pawl 38 thereon abuts the spacing sleeve 29, as shown in Figure 4. 95

Variations may be resorted to within the scope of the invention, and portions of the improvements may be used without others.

Having thus described my invention, I 100 claim:

1. In a platen-control mechanism, in combination, a platen, a ratchet-wheel, an operating handle having an inwardly-directed hub on which said ratchet-wheel is revolubly mounted, a guide-wheel on the end of said hub, means on the handle for driving the ratchet-wheel, a spring on said guide-wheel, and rotating connections between the ratchet-wheel and the platen. 105

2. In a platen-control mechanism, in combination, a frame and a platen supported therein, a bracket on said frame and adjustable to change the position of the platen-axis, a ratchet-wheel, an operating handle having an inwardly-directed hub on which the ratchet-wheel is rotatably mounted, a gear-wheel also on said hub and fast to the ratchet-wheel to rotate therewith, a grooved guide-wheel on the end of said hub, a tensioned pull-spring arranged on said guide-wheel and having one end fixed thereto, its other end being anchored, and a gear-pinion in mesh with said gear-wheel whereby the platen may be rotated. 110 115 120

3. In a platen-control mechanism, in combination, a frame, a platen supported thereby, a bracket, means for adjustably connecting it to said frame, said means including screws, one of which is passed through the bracket and threaded into the frame, the 125 130

- other being threaded through the bracket and resting on said frame, a segmental gear-rack, a rock-plate, a toothed dog pivoted to the rock-plate, means for urging the dog into engagement with the gear-rack, a spring-controlled operating handle having an inwardly-extending hub, a ratchet-wheel loose on said hub, a pawl on the handle to engage the ratchet-wheel, a pin on said rock-plate against which the handle normally rests, said pin having a head with which the pawl normally engages to hold it raised from the ratchet-wheel, and rotating connections between the wheel and the platen.
4. In a typewriting machine, a rotary platen and means for effecting a predetermined line-spacing movement thereof including an adjustable bracket, a plate attached thereto, a gear-rack, a shaft extending from said plate to rack, an operating handle having a sleeve mounted on said shaft, a ratchet-wheel on said sleeve, a grooved guide-wheel keyed to said sleeve, a spiral spring extending partially around said wheel in its groove, said handle having a pawl to drive the ratchet-wheel, a rock-plate having a pin to normally engage the pawl to hold it away from the ratchet-wheel, means on said rock-plate and engaging said gear-rack to hold the plate in predetermined position, means at the end of the handle-stroke for forcing the pawl into positive interlocking engagement with the ratchet-wheel, and rotating connections between the ratchet-wheel and the platen.
5. In a typewriting machine, a rotary platen and means for effecting a predetermined line-spacing sweep-movement thereof including a pivoted handle having a sleeve, a ratchet-wheel loose on said sleeve, a pawl on said handle to actuate the ratchet-wheel, said pawl having a tail-piece, means connected to the end of the sleeve for urging the handle rearward on its pivot, means engaging the tail-piece to hold the pawl in inoperative position, and rotating connections between the ratchet-wheel and the platen.
6. In a platen-control mechanism, in combination with a platen, an adjustable bracket, a segmental gear-plate supported thereby, a shaft extending from one to the other, a rock-plate on said shaft, a pin extending backwardly therefrom, means on said rock-plate and engaging said gear-plate to hold the rock-plate in predetermined position, a spring-urged handle having a sleeve-hub mounted on said shaft, interconnected ratchet and gear wheels loosely mounted on said sleeve, a pawl on said handle to actuate the ratchet-wheel, a portion of said pin being in a position to act as a rest for the handle, another portion acting to maintain said pawl in the inoperative position, and a connection between the gear-wheel and the platen whereby it may be rotated.
7. In a platen-control mechanism, in combination with a platen, an adjustable bracket, an arcuate plate having scale-markings thereon, a fixed plate supported by said bracket, a fixed shaft between the two, a rock-plate on said shaft, means for locking said rock-plate to said fixed plate, a pointer carried by the rock-plate and ranging over the scale-plate, a spring-urged operating handle having a sleeve mounted on said shaft, rotation-multiplying means interposed between said handle and the platen, part of said last-mentioned means being mounted on the sleeve, and means for positively locking the parts at the end of the forward operative throw of the handle.
8. A platen-control mechanism including a bracket, an operating handle having an integral tubular hub, interlocked ratchet and gear wheels revoluble on said hub, a grooved guide-wheel keyed to the end thereof, a spiral spring carried partially around the guide-wheel and having one end attached thereto, its other end being anchored to urge the handle rearwardly, a segmental gear-plate supported by the bracket, a shaft extending from one to the other on which the handle oscillates, a rock-plate on said shaft, a dog on said rock-plate to normally interlock with the gear-plate, a stop passing through the gear-plate and into the path of the rock-plate to limit the back movement of the parts, said stop being removable to permit of further backswing of the parts, means for positively locking the parts when the handle is at its forward limit of movement, and a rotating connection between the gear-wheel and the platen to rotate the same.
9. In a platen-control mechanism, the combination with a bracket mountable on the platen-frame and a shaft supported by said bracket, of a unitary assembly including a lever having a laterally-extending hub arranged to be journaled on said shaft, a ratchet-wheel, having a gear-wheel connected therewith, loosely mounted on said hub, a spring-supporting member rigidly mounted on said hub, and a driving connection between said lever and said ratchet-wheel.
10. In a platen-control mechanism attachable to the platen-frame of a typewriting machine, the combination with mechanism including a lever having a hub-sleeve to be pivoted for imparting rotation to the platen of said machine, of means for resiliently urging said lever constantly in one direction, said means including a guide-wheel rigidly provided on said hub and spaced from said lever, and platen-rotating elements arranged between said lever and said guide-wheel coaxial therewith.
11. In a platen-control mechanism for a typewriting machine, the combination with mechanism including a lever having a hub-sleeve pivoted upon an axle for imparting predetermined one-way rotation to the platen of

said machine, of a housing including two side plates to surround said mechanism and to carry said axle, said lever being located adjacent the one side plate, a guide-wheel fixed upon said hub adjacent the other side plate, and a spring upon said guide-wheel to resiliently urge the lever constantly in one direction, said spring anchored upon said last-mentioned adjacent side plate.

10 12. In a platen-control mechanism, in combination, a platen mounted in a platen-frame, a bracket attachable to the platen-frame, a plate rigidly spaced from said bracket, platen-rotating elements including an operating lever for predetermined one-way rotation of the platen and formed with an inwardly-extending hub to be pivoted between said bracket and said plate, a guide-wheel rigidly mounted upon the end of said hub, a spring 15 upon said guide-wheel having one end fixed thereto, its other end being anchored, a ratchet-wheel, a gear interlocked with said ratchet-wheel, the both rotatably mounted upon the hub to be confined between the operating lever and the guide-wheel, means on the lever for driving the ratchet-wheel, a gear-pinion in mesh with said gear-wheel whereby the platen may be rotated, an arcuate scale-plate 20 upon the bracket and under which said hub extends and which encases the wheels upon said hub, and a pointer settable along said scale-plate to determine the normal position of the operating lever.
